UNITED STATES PATENT OFFICE

THOMAS KLOSS, OF CHICAGO, ILLINOIS

GARAGE DOOR APPLIANCE

Application filed February 26, 1929. Serial No. 342,745.

My invention relates to supports for the doors of private garages, and also to means for the retention of such doors in open position, and my main object is to provide an appliance attaining in one structure the purposes referred to.

A further object of the invention is to embody a rolling support for the door.

A still further object of the invention is to use a unitary base for the rolling support and for a stop to retain the door in open position.

Another object of the invention is to design the appliance with means to retain the door stop in inactive position and accessory means for the release of the same with the foot.

A final but nevertheless important object of the invention is to construct the same in a light and compact body, suitable for easy handling and application.

With the above objects in view and any others which may suggest themselves from the specification and claim to follow a better understanding of the invention may be gained by referring to the accompanying drawings in which—

Figure 1 is a perspective view of the typical garage door, showing the novel appliance mounted in position;

30 Figs. 2, 3, 4, are, respectively, sections on lines 2—2, 3—3, 4—4 of Figure 1;

Fig. 5 is an enlarged perspective view of the appliance as seen in Figure 1.

Referring specifically to the drawings, 10 denotes a typical private garage door, to the inner side of which the novel appliance is secured, preferably at the outer end of the door.

40 The appliance has for its foundation a vertically disposed iron strap 11, which is bored with a series of holes 12 for the application of bolts 13, screws or other suitable means to secure the strap firmly to the door. Opposite the bottom of the door, the strap is formed with a forward bend 14, which is fitted with a caster wheel 15.

About midway between its ends, the strap 11 is laterally recessed from both sides, as indicated at 16, to define two forwardly directed ears 17 disposed in vertical planes.

Between these ears lies the eye 18 of an upwardly extending rod 19, such eye being pivotally mounted on a pin 20 lodged in the ears 17. The upper end of the strap 11 is also cut in from the sides to define a clip 21 which receives the rod 19 and holds the same by spring tension.

As far as described the appliance includes first, a caster or roller support 15 which supports the outer end of the door and prevents the same from sagging, second the rod 19, which is designed to form the stop. After the garage door has been opened wide, the rod 19 is swung out and dropped to the position indicated by dotted lines in Figure 2, whereby to engage the ground and stop the return of the door from the influence of wind or other pressure. Thus, with the appliance carried by both the swinging doors of the garage, the stops 19 will retain the doors in wide open position for the unobstructed passage of the vehicle.

In order that one may not stoop to manually release the stop rod 19 from the clip 21, I have devised a handy expedient which may be actuated by foot pressure. Thus, the strap 11 is cut in from one side as indicated at 22 to define a forwardly projecting tongue 23 and in this tongue is journaled an angle hook 24. One portion of this hook is a lateral bend 25 which is disposed behind the rod 19; and other portion of the hook is the forward bend 26. When one steps on the bend 26 to depress the same, the hook will rock and impinge upon the rod 19 with the bend 25 whereby to unseat the rod from the clip 21 and cause the same to fall to the ground for service as a stop in the sense previously described. The fall of the bend 26 is limited by a lug 27 projecting laterally from the tongue 23, so that when the rod 19 is again raised to be placed into inactive position, it will bear upon the bend 25 of the angle hook 24 to restore the latter to its original position.

It will be seen that the novel appliance secures in one compact unit the use of a rolling support for the door with a stop for the same, and also a handy actuator to release the stop for service. The peculiar formation of the strap to accommodate the features of the in-

vention eliminates the use of extra parts which occasion expense, labor and tendencies toward looseness and other disorders. The appliance is capable of being produced by machine methods, and its simplicity predicates a minimum manufacturing cost.

I claim:—

A door stop comprising an integral sheet metal bracket having formed on its upper end a substantially **U**-shaped spring clip provided with laterally turned lips, outwardly bent perforated ears formed substantially midway between the ends of the bracket, a vertically swingable stop bar pivoted between said ears and normally retained in inoperative position by said **U**-shaped clip portion, an outwardly bent perforated portion arranged intermediate said lips and said ears and having a vertically movable bell crank journaled therein, said bell crank being provided with a lateral extension engageable with the stop bar to release said bar from the clip portion of the support.

In testimony whereof I affix my signature.
THOMAS KLOSS.
